(57) CLAIM

The ornamental design for a box with scent hole, as shown and described.

DESCRIPTION

FIG. 1 is a front perspective view of the box with scent hole of my design;

FIG. 2 is a front elevation view thereof;

FIG. 3 is a back elevation view thereof;

FIG. 4 is a left side elevation view thereof;

FIG. 5 is a right-side elevation view thereof;

FIG. 6 is a top plan view thereof; and,

FIG. 7 is a bottom plan view thereof.

The broken lines in the drawings depict portions of the box with scent hole that form no part of the claimed design.
